DESIGN FOR A SPECTACLE FRAME

Edward M. Splaine, Southbridge, Mass., assignor to American Optical Company, Southbridge, Mass., a voluntary association of Massachusetts

Application March 24, 1938, Serial No. 76,060

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for a Spectacle Frame, of which the following is a specification, reference being made to the accompanying drawing, forming a part thereof.

Fig. I is a perspective view of a spectacle frame embodying my design;

Fig. II is a plan view of the spectacle frame shown in Fig. I; and

Fig. III is a fragmentary sectional view taken as on line III—III of Fig. I and looking in the direction of the arrows.

The essential features of my design are shown in full lines and the temples are shown in Figs. II and III in a fragmentary condition for convenience of illustration.

The characteristic features of my design comprise broadly a pair of slender eyewires connected by a bridge member having a slender, rearwardly curved central arch portion terminating

in forwardly extending bifurcated ends secured to the eyewires and having wedge-like shields extending downwardly from adjacent the lower branches of the bifurcated portions and joined along one side thereof to the respective eyewires and adapted to blend with the eyewires adjacent the lower ends thereof. Each of the said eyewires having rearwardly extending temple supports adjacent the upper temporal sides thereof. Each of said temple supports are relatively long and slender and extend rearwardly from a point adjacent the edges of the eyewires to a slight outward bend intermediate the ends thereof when viewed from the top and have their upper and lower contour edges blended continuously with the adjacent portions of the upper and lower edges of the temples when viewed from the sides. The assembled parts are blended and shaped to have a snugly fitted appearance when on the face.

I claim:

The ornamental design for a spectacle frame, substantially as shown and described.

EDWARD M. SPLAINE.
